BATTERY POWERED VACUUM CLEANER

Alvin Polatchek, New York, N.Y., assignor to Shields,
Inc., Attleboro, Mass., a corporation of Massachusetts

Filed Mar. 2, 1964, Ser. No. 78,844

Term of patent 14 years

(Cl. D9—2)

FIG. 1 is a side elevational view of a battery powered vacuum cleaner showing my new design, with the dust bag shown in phantom;

FIG. 2 is a front elevational view thereof;

FIG. 3 is a fragmentary bottom plan view thereof;

FIG. 4 is a top plan view thereof; and

FIG. 5 is a side elevational view of the side opposite that shown in FIG. 1 with the dust bag deleted.

The dominant features of my design reside in the portions shown in full lines.

I claim:

The ornamental design for a battery powered vacuum cleaner, as shown and described.
